DES. 1983

Letters Patent No. 1,173 Dated Aug. 16, 1863.

Design for a Statuette of Schiller.

The schedule referred to in these letters Patent and making part of the same.

To all whom it may concern:

Be it known that I, Edward J. Huntzger, of the City, County and State of New York, have invented or produced a new and original design in Sculpture; and I do hereby declare that the following is a full and exact description of the same.

Statuette of Schiller.

The figure of Schiller, dressed in the costume of his time, the cloak drooping from his right shoulder, gathering in folds as it falls upon an emblem of poetry at the right side of the figure. This emblem takes somewhat the form of a Greek Hermes, with wings, finishing in an ornament. The forefinger of the left hand, resting on his cheek, the figure of Schiller bends his head in a meditative attitude. The right hand, which holds a book, rests lightly upon the bust, a lyre adorns the pillars of the Heavens, around which an ivy is also twined. The head of the bust is also crowned with a laurel wreath; all of which are clearly seen in the accompanying photographs, and what I claim as my invention or production and desire to secure by Letters Patent is

The design of a Statuette of Schiller as shown and described.
